UNITED STATES PATENT OFFICE.

CHARLES E. OXFORD AND JOHN A. UPCHURCH, OF BUCKNER, ARKANSAS.

CULTIVATOR.

1,096,560.

Specification of Letters Patent. Patented May 12, 1914.

Application filed July 26, 1913. Serial No. 781,353.

To all whom it may concern:

Be it known that we, CHARLES E. OXFORD and JOHN A. UPCHURCH, citizens of the United States, residing at Buckner, in the county of Lafayette, State of Arkansas, have invented a new and useful Cultivator, of which the following is a specification.

This invention relates to cultivators, one of its objects being to provide a simple and compact structure of this type utilizing means whereby the teeth or shovels at the two sides of the central draft beam can be adjusted angularly relative to said beam so as thus to throw the loosened soil toward or away from the rows between which the machine is moving.

Another object is to provide means whereby the series of teeth or shovels located at the sides of the beam can be adjusted horizontally so as to engage the ground along either forwardly or rearwardly converging lines.

A further object is to provide a cultivator the parts of which can be easily manipulated.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

In the accompanying drawings the preferred form of the invention has been shown.

In said drawings:—Figure 1 is a plan view of the cultivator. Fig. 2 is a section on line A—B Fig. 1, said section being enlarged. Fig. 3 is an enlarged section on line C—D Fig. 1. Fig. 4 is a view partly in elevation and partly in section through the lower end portion of one of the adjustable braces. Fig. 5 is a front elevation of one of the stem supporting eyes. Fig. 6 is a rear elevation of one of the stem supporting and engaging eyes. Fig. 7 is a perspective view of the front end portion of one of the stems for engaging the eye shown in Fig. 6. Fig. 8 is an end elevation of one of the locking elements used in connection with the harrow. Fig. 9 is a plan view thereof. Fig. 10 is a perspective view of one of the hinge plates

and the adjacent portions of the arcuate members hingedly connected thereto.

Referring to the figures by characters of reference 1 designates the central draft beam of the cultivator, the same having handles 2 diverging upwardly from the rear portion thereof and fixedly secured to the beam in any suitable manner. Secured to the bottom of the beam are front and rear hinge plates 3 to which are hingedly connected front and rear straight arms 4 extending from the ends of arcuate members 5 located at opposite sides of the beam 1. Each of these members 5 is formed in its inner and outer edges with notches 6 arranged in pairs and, moreover, each of these arcuate members supports a slide in the form of a split sleeve 7 the end portions of which bear downwardly on the arcuate members 5 and have notches 8 therein adapted to register with any of the notches 6. These slides 7 have threaded studs 9 extending downwardly therefrom and secured to flat metal cross strips 10 hingedly connected, at their inner ends, to plates 11 which are arranged under beam 1 and each connected thereto by a single pivot bolt 12 whereby the plate is free to swing relative to the beam 1. A post 13 extends upwardly from each of the front strips 10 and has a locking lever 14 pivotally connected to it, this lever being provided with spaced lugs 15 adapted to extend downwardly into the notches 8 and also into any of the notches 6 which may be registering therewith. With the lever thus positioned it will be seen that the strip 10 on which the lever is mounted and the slide 7 carried thereby are prevented from shifting about the bolt 12 or relative to the arcuate member 5.

Each of the front strips 10 has eyes 16 thereunder and connected thereto by threaded studs 17. Each eye has a conical counter bore 18 in its back face, this counter bore being toothed, as shown in Fig. 6.

Plates 19 similar to the plates 11 are arranged under beam 1 back of the plates 11 and hingedly connected to these pivoted plates 19 are oppositely extending strips 20 preferably formed of flat metal. These strips extend under the arcuate members 5 and have eyes 21 thereunder connected to the strips in any suitable manner, as by means of stems 22, the heads 23 of which are

arranged within counter sinks in the upper faces of the strips 20. The outermost ones of these eyes 21 may be provided with threaded studs 24 instead of the stems 22. 5 these studs extending loosely through conical apertures 25 formed in the curved ends 26 of braces 27. Each brace is made up of two rods connected by a turn buckle 28, the inner rod 29 being loosely mounted on a 10 stem 30 projecting upwardly from the beam 1, said rods 29 being held on the stem by a nut 31 or the like. Obviously by rotating the turn buckles 28, the outer ends of the strips 20 can be swung upwardly or permitted to swing downwardly, thus adjusting 15 the strips 20 angularly relative to the beam 1.

Extending loosely through the eyes 21 are cylindrical stems 32 projecting forwardly 20 from spring standards which are curved downwardly and rearwardly and either directly engage the soil or are provided with shovels for engaging the soil. The front ends of the stems 32 are frusto-conical, as 25 shown at 34 and are toothed so as thus to fit snugly within the toothed counter bore 18, there being a threaded stud 35 extending forwardly from the stem 32 and through eye 16, this stud being engaged by a nut 36 30 whereby the conical portion 34 can be clamped tightly against the counter bore 18.

As shown in Fig. 1 the front edges of the strips 10 may be notched to form angular lugs or ears 37 adapted to be engaged by 35 the corners of the nut 36 so as thus to hold said nut against accidental displacement which might result in loosening the stem 32.

It will be apparent that by providing a structure such as herein described, the 40 standards 33 can be adjusted angularly about the longitudinal axes of the stems 32 and the strips 10 and 20 can be adjusted angularly about their connections with the plates 11 and 19. Furthermore, by disengaging the levers 14 from the arcuate members 5, the strips 10 and 20 can be adjusted 45 horizontally so as to cause the points of the teeth or shovels to engage the soil along lines converging either forwardly or rearwardly or along a transverse or oblique line, as desired. By adjusting the outer ends of the strips 10 and 20 downwardly or upwardly, the device can be used for cultivating listed crops. Various other uses can be 50 found for the cultivator and which are possible by reason of the different adjustments which can be made. The strips 10 and 20 can be connected by pivoted braces 38.

In addition to the standards 33 herein de-

scribed, central pivoted braces 38 may be 60 secured to the bottom of the beam 1. This standard is not adjustable.

What is claimed is:—

1. A cultivator including a central beam, oppositely disposed segmental members connected to the beam, a slide engaging each of said members, front and rear cross strips extending beyond each side of the beam and mounted to swing horizontally relative to the beam, means carried by the front cross strips and coöperating with the segmental members for holding said strips against horizontal swinging, and soil engaging elements connected to the laterally extending strips. 75

2. A cultivator including a central beam, oppositely disposed segmental members hingedly connected thereto, front and rear cross strips hingedly connected to the beam and extending from opposite sides thereof, soil engaging devices connected to said cross strips, means for adjusting the cross strips angularly relative to the segmental members, and means for adjusting the cross strips angularly in a vertical plane. 80

3. A cultivator including a beam, oppositely extending cross strips hingedly connected thereto, soil engaging devices connected to the strips, sectional braces loosely connected to the outer ends of the cross strips and to the top of the beam, and a turn buckle connecting the sections of said braces for adjusting the cross strips angularly. 85

4. A cultivator including a beam, front and rear cross strips connected thereto, soil engaging devices having forwardly extending stems, means upon the rear cross strips for supporting the stems for rotation, each of said stems having a toothed tapered portion at its front end and a stud projecting from said portion, means upon the front cross strips for receiving the studs and tapered ends, said means having toothed tapered counter bores for engaging the tapered portions on the stems, and means engaging the studs for binding said tapered portions of the stems within the tapered counter bores. 95

In testimony that we claim the foregoing 100 as our own, we have hereto affixed our signatures in the presence of two witnesses.

CHARLES E. OXFORD.
JOHN A. UPCHURCH.
